UNITED STATES PATENT OFFICE.

JESSE C. BOYD, OF MILROY, INDIANA.

IMPROVEMENT IN SHOVEL-PLOWS.

Specification forming part of Letters Patent No. 58,581, dated October 9, 1866.

To all whom it may concern:

Be it known that I, JESSE C. BOYD, of Milroy, in the county of Rush and State of Indiana, have invented certain new and useful Improvements in Shovel-Plows; and do hereby declare that the following is a full, clear, and exact description of the same, reference being had to the accompanying drawings and the letters of reference marked thereon, making a part of this specification.

In the annexed drawings, A A represent two beams, which are secured a suitable distance apart and attached to the horizontal beam C by means of swivels H H. At the rear end of each of said beams are small uprights, to which are secured the shovels D D.

E E are suitable handles, which are supported by the extended portions of the plow-uprights, and are secured by the rods b b, which pass obliquely from the lower end of the handles through the beams A and upright.

B represents a beam, which is stationarily secured to the beam C and placed between the beams A A. This beam B extends farther to the rear than the beams A A, and is also provided with a shovel.

F F are two straight metal bars provided with slots, as shown, near their inner ends, and secured to the beams A A. The inner ends of these bars are connected to the beam

B by means of the set-screw t, and can be adjusted so that the beams A A will be near or far from beam B, as desired.

K represents the single-tree, which is attached to the horizontal beam C and the hoop I.

In the operation of this shovel-plow, it will be seen that the beams A A, turning upon their swivels H H, can be forced near the beam B by means of the slotted bars F F, and there firmly secured by means of the set-screw t, so that the shovels D may be worked near each other.

Having thus fully described my invention, what I claim as new, and desire to secure by Letters Patent, is—

The beams A A, in combination with the upright shovels and handles, when connected to the beam C by means of the swivels H H and attached to the beam B by slotted bars F F and set-screw t, arranged substantially as specified.

As evidence that I claim the foregoing I have hereinunto set my hand in the presence of two witnesses.

JESSE C. BOYD.
